WINDOW VENTILATOR

Filed Dec. 17, 1940

Inventor:
Arthur H. Hardy
by David Marquett-Hallar. (201)

UNITED STATES PATENT OFFICE

2,337,326

WINDOW VENTILATOR

Arthur H. Hardy, Chicago, Ill., assignor of one-half to Helen Stroehle, Oak Park, Ill.

Application December 17, 1940, Serial No. 370,516

8 Claims. (Cl. 160—179)

This invention relates to window ventilators and has especially in view certain new and useful improvements therein, whereby the same may be readily fitted to any size window casing, and which is so constructed that it will not interfere with the raising or lowering of the window to regulate the volume of air admitted to a room, and at the same time will serve as a screen to prevent the entrance of rain, snow, or the like.

The main object of my invention is to provide a ventilator which has means that serves the dual function of providing ventilation and filtering of the air admitted thru the ventilator, filtering from the air such foreign matter as soot, dust and the like, thus actually air-conditioning the room by admitting only clean, pure and fresh air.

Another object of my invention is to provide a ventilating means which also furnishes the added function of filtering the air admitted into a room, and the said filtering means providing a double filtering action so as to admit the purest and freshest air into a room provided or equipped with my invention.

Another object of my invention is to provide ventilator and filtering means retaining brackets which are readily attachable to and removable from a window casing, so as to facilitate their attachment or removal during the different seasonal periods of the year.

Another object of my invention is to provide a simple, practical structure, useful for the objects and purposes heretofore mentioned, efficient in its operation, rigid in structure, and of such simple elements and assembly as to warrant economical manufacture in quantity production.

Other objects and features of my invention will become apparent from the accompanying drawing, and the ensuing description, in which like numerals are used to designate like parts and in which:

Fig. 1 represents an enlarged fragmentary longitudinal cross-sectional view of that portion of a window showing my invention in place ready for actual use and operation.

Fig. 2 is a front elevation of my invention as it should be positioned facing the outside of a window.

Fig. 3 is a detailed view partially broken away of the filtering and ventilating means comprising an essential feature of my invention.

Fig. 4 is a partial transversal cross-sectional view on the line 4—4 of Figure 1.

Fig. 5 is a detailed view of the slide fastener or attaching means which may be utilized in connection with the interchangeable attachment of the filtering and ventilating means.

Fig. 6 is an enlarged longitudinal cross-sectional view on the line 6—6 of Figure 2.

Fig. 7 is a slightly modified form of a bracket retaining means to be used in connection with my invention.

Fig. 8 is an end view of the view indicated in Figure 7, shown partially in cross-section in order to bring out the details of construction.

Referring to the various views wherein like numerals are used to designate like parts, in Figure 1, 9 designates a standard window casing sill, having a lower sash 12 provided with a bottom edge 11, which when the window is closed, contacts the surface 13 of the window sill 9, thus sealing the window opening. It can be readily seen that the window sash or frame 12 will operate in the casing without interfering with my invention attached to the said window casing. The numeral 13 designates the window pane, whereas my invention is generally characterized by the numeral 14.

Referring to Figures 2 and 3 I show the retaining brackets designated 15. The brackets are made of sheet metal or other suitable material and are provided with flanges 16 which are used to secure the brackets in place by virtue of the screws 18.

The brackets are provided with slotted portions 17 on the flange 16, and clearance holes 19 are adapted to clear the heads of the screws 18, so that the brackets may be removed by merely loosening the screws 19 without removing them, and sliding the brackets 15 so that the holes 19 clear the heads of the screws 18, thus facilitating removal and resetting whenever occasion therefor arises during the annual seasonal periods.

The brackets 15 are provided as indicated in the cross-sectional view in Figure 6, with lips 20 on top and on the bottom. The top lip is for the purpose of securing slidably the top clip member 21, which is formed as indicated in the view Figure 6, having a U shaped portion 22 adapted to fit slidably over the lip 20, and a flange portion 23 bent as indicated so as to provide a smooth edge on the clip at this point.

The top retaining clip 21 and the bottom retaining clip 21 are exactly the same, except that the lower clips 21 are securely attached to the lower lips 20 of the brackets 15 as shown at 24, and are not slidably connected thereto for rea-

sions which will become apparent as the description progresses.

In Figure 3, I show a detailed drawing of the ventilating and filtering screen designated generally 25, which I use for my invention, and it is comprised of a frame-work 26 preferably rectangular in shape and provided with a center cross-brace 27 which is spot-welded to the frame 26 as indicated at 28. Over this frame-work, the filtering means which is comprised of a cover 29 made of textile or other suitable material, and which is fitted so as to stretch tautly over the frame-work 26 when the fastener 32 is closed thus securing the filtering means to the frame-work 26.

It is to be noted, that I provide by virtue of this structure, a dual filtering means so that the air passes thru the filtering section 30 and must pass also thru the filtering section 29 before it is actually admitted into the room. The filtering means 29 is shaped approximately like a pillow case or cover, and fits over the frame-work 26, being open at one end as at 31, at which end the fastener means 32 is secured, which may be the slide fastener type indicated, or snap fasteners or hooks and eyes, or any other means which may be used to advantage for holding the filtering means 29 secured to the frame-work 26.

In Figure 4, I illustrate details of the invention, and it can be readily seen how the brackets 15 may be removed by virtue of the slot 17 and the clearance slot 19.

The dotted portion 26 indicates the frame-work in another position, which indicates that the device comprising my invention by virtue of the width of the bracket sections 15 will fit adjustably within that range, so that the filtering means may be attached to windows of various sizes and widths within the range of adjustment permitted by the width of the bracket 15.

Figures 7 and 8 show a slightly modified form of the retaining means for the filtering and ventilating means, and as indicated in Figure 8, is comprised of a bracket 33, which has a U shaped portion 34 at the bottom, and to which is secured at the top a retaining bracket 38, which is preferably U shaped, and has a hole drilled therein for securing it pivotally to the bracket 33 at one of its corners by means of hollow rivets or grommets. The grommeting machine is preferably set, so that a tight fitting action will secure the grommet 39, in order that the retaining clip 38 may require some slight force to move it about its fulcrum as indicated by the dotted position in the view Figure 7.

The bracket 33 is also provided with a flange 35, which has slots 36, the bracket 33 on the front surface being provided with the screw-head clearance holes 37, in order that the bracket 33 may be attached and removed in like manner as the brackets illustrated in Figure 2 and Figure 6.

It may be deemed advisable to provide indentations in the bracket 33, on the side of the retaining clip 38, in order to more firmly secure the retaining clip when it is adapted for use in inverted position on top of a window casing to support the filtering means rigidly. Altho I indicate in Figure 1 my invention attached to a window casing at the bottom, it may also be attached at the top of such a window casing.

It goes without saying, that my invention may be applied to windows of buildings, automobiles, house trailers, aeroplanes, and such other structures utilizing window frame construction for ventilation and air conditioning.

In attaching my device to a window, it may be attached as indicated at Figure 1. The screws are preferably placed at the proper position indicated, and threaded into the casing, then the brackets are slid into place, and the screw-heads brought down to bear on the flanges 16 retaining the brackets firmly and securely in place. After each bracket is attached, the clips 21 indicated at Figure 2, are removed by sliding them off the retaining lips 20 of the bracket 15. The screen set in place in the brackets, and the clips 21 slid on to the lips 20 to retain the screen firmly in place.

In like manner, if the bracket in modified form as a retaining means illustrated in Figure 7 and Figure 8 is utilized, the retaining clips 38 are merely swung out into upright alignment so as to clear the insertion of the filtering means structure and then brought down encasing the same and holding it firmly and securely in place.

When it is desired to remove the screen, the retaining clips 21 are rotated into the dotted position indicated, then the filtering means may be removed, the fastener 32 is opened allowing the filtering sack 29 to be removed from the frame-work, and a fresh and clean filtering sack applied.

The frame-work after the fastening means 32 is secured in place, is replaced in the ventilating bracket structure, and is ready for operation and use. The clips 38 are provided with a rounded portion 40 so as to furnish ample clearance for rotation.

By virtue of the filtering sack that I provide, it will absorb all the foreign substances which are injurious, and permeate the air, and it also provides a ready means of interchangeability of the filtering medium whenever the case may necessitate. The air admitted will thus be free of pollution and contamination.

I believe that I have described in rather succinct terms the nature and description of the construction of my invention, having shown a preferred form thereof, and inasmuch as it is susceptible of many modifications, alterations, and improvements, I reserve the right to all such modifications, alterations, and improvements which come within the spirit and scope of my invention, and within the purview of the foregoing description and the accompanying drawing; my invention to be limited only by the subjoined claims.

Having thus described and revealed my invention what I claim as new and desire to secure by Letters Patent is:

1. An article of the character described comprising, air ventilating and filtering means comprising, a rigid frame member made of a band of material, and a sack member made of textile material adapted to fit tautly over the said frame member, bracket means adapted to secure removably to a window frame the said air ventilating and filtering means in overlapping relationship with the said bracket means, comprising two bracket members, each bracket member having a substantial face portion terminating at the base in a foot portion and terminating at the top in a lip portion, a side portion substantially at right angles to the said face portion, slotted portions in the said side portion adapted to receive the bodies of screw members, enlarged openings in said face portion adjacent said slotted portions adapted to clear passage therethru of heads of screw members, and a clip member adapted to engage slidably and removably the said lip portion,

2. In an article of the character described, bracket means comprising, a bracket member having a substantial face portion terminating at the base in a foot portion and terminating at the top in a lip portion, a side portion substantially at right angles to the said face portion, slotted portions in the said side portion adapted to receive the bodies of screw members, enlarged openings in said face portion adjacent said slotted portions adapted to clear passage therethru of heads of screw members, and a clip member adapted to engage slidably and removably the lip portion of the said bracket members.

3. In an article of the character described, ventilating and air filtering means made of textile material and adapted to provide dual filtering action comprising, a rigid frame member made of a band of material, a sack-like member made of textile material open at one end adapted to fit tautly over the said frame member, and fastening means secured to the open end of said sack-like member adapted to secure tautly and removably the said sack-like member to the said frame member.

4. In an article of the character described, provided with air ventilating and filtering means, bracket means removably securable to a window frame, said bracket means having a substantial face portion terminating at the base in a foot portion provided with a recess adapted to hold the said air ventilating and filtering means, and U shaped clip means articulately secured in inverted relationship at one of its ends to the said bracket means.

5. In an article of the character described, provided with air ventilating and filtering means, bracket means removably securable to a window frame, said bracket means having a substantial face portion, a window attaching portion at right angles to the said face portion, enlarged openings in the face portion of said bracket retaining means adapted to receive heads of fastening

means therethru, slotted openings in the said window attaching portion adapted to fit slidably bodies of said fastening means, the said enlarged openings merging with the said slotted openings,

5 the said bracket means provided with lip means on its top and bottom edges, and clip means slidably and removably secured to the said lip means.

6. In an article of the character described, ventilating and air filtering means adapted to provide dual filtering action, comprising, a rigid frame member made of an endless band of material having a rib element secured intermediate its ends, and a sack member made of textile material adapted to fit tautly over the said frame

15 member.

7. In an article of the character described, provided with air ventilating and filtering means, bracket means removably securing to a window frame the said air ventilating and filtering means

20 in overlapped relationship with the said bracket means, the said bracket means having a substantial overlapping face portion terminating at the base in a front portion and terminating at the top in a lip portion, and a clip member adapted 25 to engage slidably and removably the said lip portion.

8. In an article of the character described, bracket means comprising, a bracket member having a substantial face portion terminating at

30 the base in a foot portion, a side portion substantially at right angles to the said face portion, slotted portions in the said side portion adapted to receive the bodies of screw members, enlarged openings in the said face portion adja-

35 cent said slotted portions adapted to clear passage therethru of heads of said screw members, U shaped clip means articulately secured in inverted relationship at one of its ends to the top of the said bracket member, and articulate secur-
40 ing means adapted to secure the said clip member to the said bracket member.

ARTHUR H. HARDY.
